WINDOW

Alexander L. France, Albany, N. Y.

Application September 23, 1932, Serial No. 634,459

10 Claims.

(Cl. 20—46)

My invention relates to improvement in windows, and one of its objects is the provision of means for facilitating the removal of a window sash from its frame to enable, for example, its being washed on both sides, regardless of whether a storm sash or wire screen is in place in the window frame on the outer side.

Another object is the provision of means for enabling the sash, after its removal, to be hung on the inner side of the window casing in position to enable the sash to be cleaned on both sides while in one position.

Another object is the provision of means to enable the sash to be readily restored to its running ways in the casing. It is also an object to provide a sash with a side stile made in two sections, one section being a permanent section of the sash frame and the other section being detachable therefrom and attachable thereto at will by improved means, the detachable section being connected to one of the weight cords of the sash.

Another object is to provide means, comprising one of the elements of said attaching and detaching means, (namely a latching arm) for locking the said removable section to the casing when unlatched from the sash, whereby the detached section is prevented from being raised by the weight attached to its cord.

The foregoing and other objects of the invention will be hereinafter more fully set forth and claimed, reference being had to the accompanying drawings in which:—

Fig. 1 shows a window in side elevation, comprising the features of the invention.

Fig. 2 is a section taken along line 2—2, Fig. 1, and viewed in the direction of the arrows in said figure.

Fig. 3 is an enlarged view in perspective of the right hand section of the lower sash of Fig. 1 showing the box or mortise elements of the means for hanging the sash to the window casing, as indicated in Fig. 8.

Fig. 4 shows enlarged and in perspective that portion of the window between horizontal lines 4'—4' and 4''—4'', Fig. 8. This figure shows the latching arm for locking the detachable stile section, of the lower sash, against the pulling force of the sash weight.

Fig. 5 is a companion element shown in section in Fig. 10 of the attaching and detaching means shown in Fig. 4.

Fig. 6 is an enlarged view of that portion of the window frame and of the upper window sash between lines 6'—6' and 6''—6'', Fig. 8 with a portion of the stop strip broken away.

Fig. 7 is an enlarged view in perspective of a section of the spacing strip which is located in the frame between the sashes, said section being located between the parallel lines 7'—7' and 7''—7'', Fig. 1.

Fig. 8 is a view similar to that of Fig. 1, of a window comprising the features of the invention, showing the upper and lower sashes removed and hung from the casing, the lower sash on the right and the upper on the left.

Fig. 9 is a section taken on line 9—9, Fig. 8, and viewed in the direction of the arrows in Fig. 8.

Fig. 10 is a section through the elements of the attaching and detaching means shown in Figs. 4 and 5, the section being taken along lines 10—10, Fig. 4, and 10—10, Fig. 5. In this figure the elements are shown in position just about to close and while the latching arm is open.

Fig. 11 shows the elements of Fig. 10 in section after they have closed and the sections of the stile have been latched together. The latching arm is here shown closed.

Fig. 12 shows the same elements of Figs. 10 and 11 in front view but with the latching arm open as in Fig. 4.

Fig. 13 is a view similar to Fig. 11 except that it shows a metal weather strip instead of the flange element projecting from the section of the stile in Fig. 4.

Referring more in detail to the drawings, the window shown in Fig. 1 comprises the usual casing with the top and bottom sills 2 and 3 respectively and the sides 4 and 5. It comprises as usual two sashes, an upper one 6 and a lower one 7. The lower sash is provided on the right side with a pair of box or mortise elements 8 and 9 shown enlarged in Fig. 3. The upper sash is provided with a pair of similar mortise elements 10 and 11. The object of these elements is to enable the sashes to be hung from the sides of the casing as indicated in Fig. 8. Each side is provided with a pair of prong or tenon elements, each projecting away from the window opening. For example, the side 4 of the casing is provided with prongs 12 and 13 and the opposite side 5 with prongs 14 and 15. The prong 13 is shown enlarged in Fig. 6. It is made of a metal strip with arms 16 and 17 at right angles to each other. One of the arms is provided with perforations for screws 18, and extends under the stop strip 19, which in Fig. 6 is broken away to show more clearly that one of the screws is secured to the face strip 20 of the side 4 of the casing, and that the other screw is secured to the inner face

60

90

95

100

105

110

strip 21 of the same side of the casing. The prong 13 is secured in the same way to the same strips 20 and 21. The prongs on the opposite side are secured in the same way but turned in the opposite direction. In Fig. 6 the box catch 11 of the upper sash is shown in engagement with the prong 13. In Fig. 8 the upper sash is shown in position with both its box catches 10 and 11 in engagement with the corresponding prongs 12 and 13, and the lower sash is shown in position with both its box catches 8 and 9 in engagement with the corresponding prongs 14 and 15.

Referring again to Fig. 1, the lower sash is provided with a stile 22 on the right side and a stile 15 23 on the left side. The stile 23 is made in two sections 24 and 25, see Fig. 11, also Figs. 4 and 5.

When the sash is in place, as indicated in Fig. 1, these two sections of the left stile are latched together by means of latches 26, 27 and 28, each 20 of which comprises two elements shown in Figs. 4 and 5, one of which, the mortise element 29, is secured to the stile section 24 and the other of which, the tenon element 30, is secured to the stile section 25.

25 The element 30 is preferably made as a single piece of metal folded with an arm 31 across the front which arm is perforated to receive a screw 32 for securing the arm to the stile section 25. The body portion 33 of the tenon 30 forms less than a right angle with the arm 31 as indicated 30 in Fig. 10 and tapers inward so that the width where it meets the arm 31 is greater than the width at the inner end 33'. This body portion has flanges 34 and 35 which project to the right 35 at right angles therefrom, and approach each other toward the end 33' of the body portion 33. Said flanges 34 and 35 are provided in turn with flanges 36 and 37, respectively which project at right angles upward and downward respectively 40 along the left side of the stile section 25. These last flanges extend perpendicular to the arm 31. It will be seen, therefore, that the body portion and the flanges 34 and 35 form a wedge shaped 45 inclosure which tapers toward the end 33', toward a horizontal plane through the longitudinal axis of the wedge and also toward a vertical plane through the same axis of the wedge.

The mortise element 29 of the latch comprises a somewhat similar wedge shaped inclosure having 50 a body portion 38, (corresponding to the body 33 of the tenon), a pair of flanges 39 and 40, (corresponding to flanges 34 and 35), and a pair of flanges 41 and 42, (corresponding to flanges 36 and 37). This body portion and the flanges 39, 55 40, 41 and 42 form a wedge shaped inclosure (similar to that of the tenon element 30) which also tapers toward the horizontal axial plane and toward the vertical axial plane of the mortise element, which tapered inclosure is adapted to receive the tapered inclosure of the tenon 30 as indicated in Fig. 11. The mortise element 29 has a latch arm 43 which corresponds to the arm 31 of tenon 30 but which is hinged to the body portion 38 as indicated in Fig. 10. The arm 31, 60 as indicated in Fig. 10, is folded to form a mortise slot 44 for receiving a tongue 45, a part of the arm 43, which tongue may be formed by also folding the arm 43, as indicated in Fig. 10.

Referring to Fig. 10, it will be seen that a portion 70 of the metal extending from the end 38' of the body portion 38 is folded under to form a spring 45' inside the mortise. Similarly the metal extending from the end 33' of the body portion 33 of tenon 30 is similarly folded to form a spring 46. Now, when the tenon 30 enters the mortise

29 the outer surface of the spring 46 engages the inner surface of the spring 45, which springs and the wedge construction described insure a perfectly snug fit between the two elements 29 and 30. Furthermore, when the arm is closed the 80 tongue 45 is wedged in the slot 44 (due to the spring nature of the material and to the form of the slot and tongue indicated). Thus the two sections of the stile 23 may be effectively latched together by means of the three latches 26, 27 85 and 28.

Referring to the strip 19 indicated in Figs. 1 and 6, which strip is also shown in Fig. 4, two catch elements 47 and 48 are secured to the face of this strip. One of these catch elements is shown enlarged in Fig. 4. The object of these catches is to hold the stile section 24 against being raised by the weight at the end of the cord 49 (see Fig. 2) when the stile section 24 is unlatched from the stile section 25 or, in other words, when the lower sash is unlatched from the stile section 24. No such latches are necessary for the lower sash on the opposite side of the window, that is, on the right hand side, inasmuch as the stile 22 on the right side is not made in two sections. It will 100 be seen that the difference in the function of the catches 47 and 48 on the left side of the casing and in the prongs 14 and 15 on the right side thereof, Fig. 1, is that the latches 47 and 48 prevent the stile section 24, which is very light, from 105 being raised by the weight on the end of the cord 49, while the prongs 14 and 15 prevent the other portion of the sash, which constitutes the major portion of the sash and is much heavier, from falling when it is removed from the window frame, notwithstanding the cord 50, with its weight attached, remains attached to the lower sash.

Catch elements 51 and 52, similar to the catch elements 47 and 48, are provided on the opposite 115 side of the window for one of the sections 53 of the right hand stile 54 of the upper sash (which stile is made in two sections exactly as the stile 23 of the lower sash)—the other section being the stile section 55. The upper sash is also provided with latches 56, 57 and 59 exactly like the latches 26, 27 and 28 on the lower sash. The latch 28, as already explained, has a latch arm 43, and similarly, the latches 27, 26, 56, 57 and 58 have latch arms 60, 61, 62, 63 and 64 which are 125 the same as the latch arm 43. With reference to the catch elements 51 and 52, these are secured to the spacing strip 65, see Fig. 7, which is located between the two sashes and corresponds to the spacing strip 66 on the left side of the frame, see 130 Fig. 2.

Assuming that the upper and lower sashes are as indicated in Fig. 1, and that it is desired to remove them from the frame and to hang them as indicated in Fig. 8, it will be necessary first to 135 open the window lock 67, which is a lock of the usual type. Then the latch arms 43, 60 and 61 are disengaged from their corresponding latch elements and thrown open against the face of the stop strip 19, as indicated in Fig. 4, except that the arm 43 is at the time below its catch element 47. The same is true of the latch arm 61. No catch element is provided for the latch 27, although one could be provided if desired. After the latch arms are thrown open the lower 140 sash is raised to clear the lower sill and to allow the latch arm 43 to engage its catch elements 47 as indicated in Fig. 4, and to allow the latch arm 61 to engage in a similar manner its catch element 48. The lower sash is then rotated counter 145 75

clockwise as viewed from above to allow the stile section 25 to disengage from the stile section 24, after which operation the lower sash may be withdrawn entirely from the casing and hung on its prongs 14 and 15, as indicated in Fig. 8, perpendicular to the casing and without being disconnected from its right side cord.

The upper sash may then be lowered to a position with the latches 56 and 58 below their corresponding catch elements 51 and 52. The latch arms 62, 63 and 64 are now opened up until they strike the face of the facing strip 65. The upper sash is now allowed to rise until the latch arms 62 and 64 engage their corresponding catch elements 51 and 52 as the latch arm 43, Fig. 4, has engaged its catch element in that figure. The upper sash may now be rotated to the left until it clears its stile section 53, after which operation the upper sash may be removed from the window casing 20 and hung on its prongs 12 and 13, as indicated in Fig. 8, perpendicular to the casing and without being disconnected from its left side cord.

The sashes may now be washed on both sides and restored to the casing as follows:—First the upper sash is unhung from its prongs and its left side inserted in its track in the left side of the casing. The sash is then raised or lowered until the corresponding latch sections are opposite each other and brought into engagement after which the sash is lowered slightly to clear the latch arms from their catches to enable the latch arms to be closed and thus restored to their original positions. The upper sash is then raised to its place out of the way of the lower sash.

The lower sash is then unhung from its prong and its right stile inserted in its runway in the casing. The sash is then raised or lowered to bring the corresponding sections of the latch opposite each other, as was done in the case of the upper sash and as indicated in Fig. 10. These latch sections are then closed into engagement, as indicated in Fig. 12, after which the sash is lowered enough for the latch arms to clear their catch elements and enable these arms being closed as indicated in Fig. 11. The sash may then be lowered to the position indicated in Fig. 1 and the window lock again closed if desired.

Referring to Fig. 4, it will be seen that the stile section 24 is provided with a flange 67 which is adapted to engage a notch 68 in the section 25 to prevent any draft through the stile when the window is in place. Instead of this arrangement, both sections 24 and 25 may be cut away to receive a metal plate 70 as indicated in Fig. 55, 13, which plate may be screwed to the strip 24.

As indicated in Fig. 6, the latch element 29 is embedded in the strip 24 and secured thereto by screws 71. The latch element 30 is also partly embedded in the stile section 25 and secured thereto not only by screw 32 but also by screws 72 one for each of the flanges 36 and 35. The arm 31 is made flush with the face of the stile section 25, just as the flanges 41 and 42 of element 29 are flush with the side face of the strip 24 which side face meets the flange 67 as shown.

Referring to the catch element in Fig. 7, this catch is embedded in the strip 65 so that the outer surface 72 of the catch prong 73 is flush with the front face 74 of the strip 65 and also flush with the surface 75 of the lower portion of the base branch of the catch, in the region of the head of the lower screw 76, which lower screw and the similar upper screw 76 secure the catch to the strip. It will be seen that the upper portion of the base frame portion of the catch, that

is the portion under the prong 73 is angular, it being depressed below the prong. Also it will be seen that the strip 65 is cut away transversely to form a passage 74 to allow the latch arm of the latch 56 (which arm corresponds to the latch arm 43, Fig. 4) to pass under the prong 51. It will be noted that the base frame of the catch Fig. 4 is straight, instead of angular, in form, as the base frame of the catch 51, and also that the base frame is flush with the face of the stop strip 19.

Referring to Fig. 3, it will be understood that the box catches 8 and 9 are flush with the surface 75 of the sash. It will also be understood that the cord 76, see Fig. 3, which extends along the groove 77 of the sash passes behind the box catch 8 and terminates in the usual knot in the bore 78, the axis of which inclines upward. By this arrangement the retention of the cord in the groove is insured when the sash leaves the casing and is hung as in Fig. 8.

In the construction of the latches, mortise, tenons, catches, prongs and the like, I find that tool steel may be used but any other suitable material may be employed.

It will be understood that while I have elected to illustrate my invention by embodying them in the form of the drawings, I do not wish to be so limited as the principles of the invention are of broad application, as indicated by my claims herein, and may be embodied in various forms.

What I claim is:—

1. In a window, in combination, a casing and a sash having a stile divided in two sections, interlocking means for securing said sections together, said means comprising a mortise element secured to one of said sections and a tenon element secured to other of said sections, and means for latching said mortise and tenon elements together after they have been interlocked, said latching means last mentioned comprising a mortise element and a corresponding tenon element, one of the said elements of said latching means last mentioned being hinged to the corresponding one of said sections. 110

2. In a window, in combination a casing and a sash having a stile on each side, one of said stiles being divided in two sections, interlocking

means for securing said sections together, said means comprising a mortise element secured to one of said sections and a tenon element secured to the other of said sections, said sash having cords and weights attached thereto threaded with said casing, and means whereby the sash may be hung to the window casing after the sash is removed from the casing runway and while connected to one of its cord and weights, said last means comprising a mortise element and a corresponding tenon element, the mortise element being secured to the other of said sash stiles 125

with the opening perpendicular to the face of its stile and the tenon being secured to said casing parallel to the face of the casing whereby the sash may be hung perpendicular to the casing outside the casing frame. 130

3. In a window, a sash having a stile on each side, one of said stiles being made in two sections, interlocking means for securing said sections together, said means comprising a mortise element secured to one of said sections and a 145 tenon element secured to the other of said sections, one of the weight cords of said sash being secured to one of said sections, and means comprising an element hinged to said mortise element for latching said section last mentioned to said 150

casing and means on said casing for engaging said latching means.

4. In a window, in combination a casing and a sash having a stile divided in two sections, interlocking means for securing said sections together, said means comprising a mortise element secured to one of said sections and a tenon element secured to the other of said sections, and means comprising an element hinged to said mortise element for latching said section last mentioned to said casing, to prevent the section from sliding in the casing said last means comprising a mortise element and a corresponding tenon element, one of said last mentioned elements being secured to the casing and the other to the said stile section last mentioned.

5. In a window in combination a sash having a stile on each side, one of said stiles being divided in two sections, interlocking means for securing said sections together, said means comprising a mortise element secured to one of said sections and a tenon element secured to the other of said sections, and means comprising an element hinged to said mortise element for latching said section last mentioned to said casing, to prevent the section from sliding in the casing said last means comprising in turn a mortise element and a corresponding tenon element, one of said last mentioned elements being secured to the casing and the other to the said stile section to which said cord is connected, said last mentioned elements being hinged to its support whereby it may swing into engagement with either the said element secured to the casing or with its corresponding element on the main section of the sash.

40. 6. In a window, in combination, a sash having a stile on each side, one of said stiles being made in two sections interlocking means for securing said sections together, said means comprising a spring mortise element secured to one of said sections along an edge of said section and a spring tenon element secured to the other of said sections along an edge of said other section said spring elements being located in operative relation, whereby the tenon may enter the mortise and draw the two sections snugly together with said springs enclosed between said sections, and latch means comprising a tenon element hinged to said spring mortise element along the face of the sash, and comprising also a mortise element formed in the face of the sash in a section of said spring tenon element.

7. In a window, in combination, a casing and a sash therefore, one of the stiles of said sash being divided into two sections, one of said sections engaging a runway in the casing and the other

section being integral with the central portion of the sash, means for latching said sections comprising mortise and tenon elements and means for latching said elements together comprising an element rotatably secured to one of said elements, the axis of rotation being parallel to the face of the casing.

8. In a window, in combination, a casing and a sash therefore, one of the stiles of said sash being divided into two sections, one of said sections engaging a runway in the casing and the other section being integral with the central portion of the sash, means for latching said sections comprising mortise and tenon elements, and means for latching said elements together comprising an element rotatably secured to one of said elements, the axis of rotation being parallel to the face of the casing, means for latching said sections together comprising mortise and tenon means located between said sections and also mortise and tenon means along the face of the window.

9. In a window, in combination, a casing and a sash therefore, one of the stiles of said sash being divided into two sections, one of said sections engaging a runway in the casing and the other section being integral with the central portion of the sash, means for latching said sections comprising mortise and tenon elements, and means for latching said elements together comprising an element rotatably secured to one of said elements, the axis of rotation being parallel to the face of the casing, means for latching said sections together comprising mortise and tenon means located between said sections and also mortise and tenon means along the face of the window, the tenon of one of said means and the mortise of the other of said means being made as a unit.

10. In a window, in combination, a casing and a sash therefore, one of the stiles of said sash being divided into two sections, one of said sections engaging a runway in the casing and the other section being integral with the central portion of the sash, means for latching said sections comprising mortise and tenon elements and means for latching said elements together comprising an element rotatably secured to one of said elements, the axis of rotation being parallel to the face of the casing, means for latching said sections together comprising mortise and tenon means located between said sections and also mortise and tenon means along the face of the window, the tenon of one of said means and the mortise of the other of said means being made as a unit, the tenon of one of said means being hinged to the body of the mortise element of the other of said means along an axis parallel to the face of the window.
